UNITED STATES PATENT OFFICE.

RAYMOND A. BRECUNIER, GEORGE SHERRILL, AND ALLAN D. DONNELL, OF WATERLOO, IOWA, ASSIGNORS TO THE RATH PACKING COMPANY, OF WATERLOO, IOWA.

COMBINATION SHIPPING SLIP.

Application filed December 2, 1927. Serial No. 237,172.

Our invention relates to improvements in combination shipping slips, and the object of our improvements is to furnish for shippers a convenient device of this class having 5 like parts arranged for sequential separation from each other at different initial stages of handling of a package or container upon which one part is permanently secured, whereby a consecutive check and record is 10 made of each such stage of handling to be ultimately assembled for recording and preservation.

This object we have accomplished by the means which are hereinafter described and 15 claimed, and which are illustrated in the accompanying drawings, in which Fig. 1 is a plan of a slip embodying our invention, as its upper surface appears before folding. Fig. 2 is a plan of the opposite face of the slip as 20 before such folding. Fig. 3 is a top plan of one of the divisional parts of the slip as secured upon a supporting surface, the other divisional parts having been sequentially removed, except separable end margins thereof 25 which are in this figure shown as also secured upon the supporting surface idly.

Our invention is not restricted to the precise construction and arrangement of parts herein shown and described, nor to the various details thereof, as the same may be modified or rearranged in various particulars without departing from the spirit and scope of our invention, one practical embodiment of which has been herein illustrated and described without attempting to show all of the various modifications in which our invention might be embodied.

Our improved combination shipping slip is particularly designed for use by large shippers of goods, who place in a particular car or other means for transportation packages or containers of goods to be delivered thence to different consignees at one station. The intention is to prevent confusion or errors in 40 the distributions at the different initial stages of transference of the goods to the means for transportation, and by the means we supply herein checking of such stages may be had sequentially, and the check slip parts as removed from the slip at each such stage later assembled for comparison, recording and filing.

Referring to Figs. 1 and 2 in which our shipping slip is spread out flatly before folding, the numerals 1, 2 and 3 denote parts of

the slip having upon one face of each identical printed matter, such as indicative numbering, directions, and other words or inscriptions, together with a portion subdivided by means of ruled lines to receive at *d* entries 60 of goods shipped and to which the shipping slip refers. For instance, at *a* is a serial number for the whole shipment and this number appears on each of said inscribed slip parts. Said slip parts also display at *e* sequential 65 numerals, such as 1, 2 and 3 for the three slip parts for detachment at different stages of handling of the goods initially before the actual storing of the package to which they refer, in a car reserved for them and whose 70 car number may be entered at *b*. Other insertions may be made at *c* and *f* as indicated by the reference words.

The slip may be rendered more easily tearable transversely at suitable places by means 75 of lines of perforations at *g*, *h*, *i* and *l*, and these perforated lines also serve as places for folding over the parts of the slip upon each other before any of the parts 1, 2 and 3 are separated at the different stages of handling 80 of the package. The perforated line *g* sets off at the left hand a narrow end strip or margin 4, while the perforated lines *h* and *l* separate from the inscribed slip parts 1 and 2 an interposed narrow strip 5 whose use as 85 also that of the other strip 4 will be described.

It should be noted that the printed matter upon the spaced slip parts 1 and 3 appears upon the upper face of the slip before folding, while the printed matter upon the slip part 90 2 appears upon the under face of the slip before folding.

When a package of goods is ready in the shipping room of a plant, the slip, its parts 1, 2 and 3 previously inscribed with all necessary entries relating to the goods, the reserved car therefor and other data, is pasted or otherwise secured as a whole after folding of its parts upon each other in registering superposition, upon the package.

The manner of folding is to position the slip part 3 next to the package, folding the slip part 2 at the line *h* thereover in registration, with the strip part 5 extending beyond the part 3 to the right, then refolding 105 the slip reversely along the perforated line *h*, so that the printed face of the part 2 which is uppermost is covered in registration by the part 1 whose printed face is also now uppermost, because the said part is longer than 110

the underlying part 2 as a blank space is left at the right hand of the part 1 to overlay the said strip part 5. The end marginal strip 4 will then project beyond the part 2 at the 5 left and contact with the package. As thus folded, the rear faces, alined, of the slip parts 3, 4 and 5 may be pasted upon the package permanently. The slip parts 1 and 2 are thus held at both ends to the package and 10 against accidental removal from the part 3 and said package.

When a shipment is to be made, the uppermost inscribed slip part 1 may be removed for 15 checking there by tearing the slip at the perforated lines *g* and *h*. This exposes the slip part 2 beneath, which may be similarly removed when the package is placed in the car, and preserved there for checking purposes, and to be compared with the part 1 later be- 20 fore also comparing them with the book entry of the shipment. Errors are thus easily detected before departure of the car, and packages for consignees at the same station seg- 25 regated properly for and in the reserved car. The end strips 4 and 5 remain upon the pack- 30 age, as their only use is to intially secure the ends of the slip parts 1 and 2 in super- position over the part 3 before removal of said parts 1 and 2 successively at the sequen- tial stages therefor.

While the securing strips 4 and 5 may be omitted without departing from the principle of our invention, yet their use tends to prevent loss of the loosely positioned parts 1 and 35 2 by accident.

It is to be understood, that but two like inscribed slip parts may be used or any other number thereof than those illustrated without departing from the invention.

40 Carbon paper or transfer coats may be used at the back of the parts 1 and 2, so that a written inscription made upon the part 1 will be identically transferred to the under-lying parts 2 and 3, if desired. The backs 45 of the parts 3, 4 and 5 may be given a gummed coating.

Having described our invention, what we claim as new, and desire to secure by Letters Patent, is:

1. A combination shipping slip, comprising detachably connected portions in triplicate of which end portions on one face and an intermediate portion on the opposite face contain the same reserved blank spaces with adjacent inscribed designations therefor, one end portion having a blank end tab at its outer end, and having at its opposite end a like blank end tab integrally connecting it to said intermediate portion, so that when the slip is folded upon itself with the intermediate and the other end portion in piled registration and their inscribed faces presented outwardly, and the first-mentioned end portion is folded in like registration upon said other portions, the said end tabs will project oppositely beyond all the said piled portions. 50 55

2. A combination shipping slip, comprising detachably connected portions in triplicate of which end portions on one face and an intermediate portion on the opposite face contain the same reserved blank spaces with adjacent inscribed designations therefor, said portions being numbered serially and all having a common identification inscription, one end portion having a blank end tab at its outer end and having at its opposite end a like blank tab integrally connecting it to said intermediate portion, so that when the slip is folded upon itself with the intermediate and the other end portion in piled registration and their inscribed faces presented outwardly, and the first mentioned portion is folded in like registration upon said other portions, the said end tabs will project oppositely beyond all the said piled portions. 60 65 70 75 80 85

In testimony whereof we affix our signatures.

RAYMOND A. BRECUNIER.

GEORGE SHERRILL.

ALLAN D. DONNELL.
